UNITED STATES PATENT OFFICE

2,532,508

ELECTRONIC INTERRUPTER

Walter P. Menkhaus, Philadelphia, Pa.

Application December 27, 1946, Serial No. 718,863

1 Claim. (Cl. 175—373)

1

The object of the invention is to provide improvements in electronic interrupters of widely separated maximum and minimum period limits of operation.

More particularly an object of the invention is to provide an interrupter of this type, which is adapted for use in controlling the operation of such devices as intermittent test apparatus, flash signs such as are used for advertising, warning and other devices by which the periods during which the controlled device is energized and deenergized may be the same, or in which these periods may be widely different, as for example as short as one-thirtieth of a second to a full minute or more.

A further object is to provide a completely automatic device of this class, which eliminates the present necessity of using any form of motor and commutator whatsoever, and which provides variable controls so the device can be set for predetermined periods of "on" and "off," whether such periods are equal or different.

And a more specific object is to provide a device of this nature, which comprises the assembly of an auto-transformer, a relay, a rectifier and a thyratron tube, both fixed and variable potentiometers or resistors, switches, and fixed condensers, so interconnected as to provide a simple and compact device of low initial cost, relatively no cost of upkeep and readily adjusted and repaired by replacement of parts, and one which can be easily transported from place to place, consumes a minimum of current, and is highly efficient in operation.

Having thus described the objects in general terms, the invention comprises further details of construction and operation, which are herein-after brought out in the following description, when read in conjunction with the accompanying drawings, in which Fig. 1 is a wiring diagram illustrating the elements comprising one embodiment of the invention with appropriate electric connections; and Fig. 2 is a modified embodiment of the same.

Referring to Fig. 1 of the drawing, a two-pronged plug 1 is employed to represent any suitable means for readily connecting the device in an ordinary alternating current circuit, such as the widely used 110-115 volt, 60-cycle, circuit of commercial and domestic installations so prevalent throughout the United States.

One side of said plug is connected through a switch 2 to the primary winding 3 of a filament and bias transformer 3' of the iron-core type, the secondary winding 4 of said transformer being connected to the respective filaments 5 and 6 of a pair of tubes 7 and 8, the first of said tubes being a one-half wave rectifier and the other tube being of the thyratron type. The opposite end of the transformer primary is connected by a wire 9 to

2

the opposite side of said plug 1. A continuation 10 of said primary winding 3 is also connected by a resistance 11 to said opposite side of said plug, said resistance having a variable positioned tap 12, connected as hereinafter described.

From said switch 2 a wire 13 leads through a switch 14 to the coil of a relay 15, having in sequence (when said relay is deenergized) a closed contact 16, three open contacts 17, 18 and 19, and a closed contact 20. The first-mentioned contact 16 is interposed between the wire 13 and the plate of the rectifier tube 7, the cathode of which tube is connected through a pair of variable resistances or potentiometers 21 and 22, a condenser 23 and wire 24 to the second or opposite side of said plug as shown, said last-mentioned resistance 22 being shunted by a switch 25.

The connection between said resistance 22 and said condenser 23 is connected by wire 26, first through a fixed resistance 27 to the control grid 28 of the second tube 8, and secondly through the open relay contact 18 to a variable resistance 29, fixed resistance 30 and second variable resistance 31 to a wire 32, which is connected to the wire 24, said last-mentioned variable resistance 31 being shunted by a switch 33.

The wire 34 that connects the resistance 27 to the control grid 28 of the second tube 8 is connected through a fixed resistance 35 and the open relay contact 19 to a second fixed resistance 36 and thence to said wires 32 and 24. Said fixed resistance 35 is also connected through a variable resistance 37, shunted by the closed relay contact 20, to the tap 12 of the resistance 11 by a wire 38. It will also be noted that the shield or suppressor grid 39 and cathode 40 of the tube 8 are connected by a common wire 41 both to the wires 32 and 24, and also to a terminal 42. The opposite side of the relay 15 is connected to the plate of the tube 8. Wire 13 is connected through the open relay contact 17 by a wire 43 to a second terminal 44.

In the embodiment of the invention herein described and illustrated, the following values are preferred as having been successfully tested and proved:

Variable resistance 21—50,000 ohms
 Variable resistance 22—10 megohms
 Condenser 23—4 microfarad; 200 volt
 Fixed resistance 27—20 megohms; $\frac{1}{2}$ watt
 Variable resistance 29—50,000 ohms
 Fixed resistance 30—300 ohms; $\frac{1}{2}$ watt
 Variable resistance 31—10 megohms
 Fixed resistance 35—20 megohms; $\frac{1}{2}$ watt
 Fixed resistance 36—20 megohms; $\frac{1}{2}$ watt
 Variable resistance 37—1 megohm
 Variable resistance 11—1 megohm

For using the improved interrupter, a chart is provided to show the combination of switches to be closed and/or opened, and the adjustment of

the respective resistances, in order to provide any desired period of energizing and deenergizing the controlled apparatus that may be connected to the output terminals 42 and 44.

For purposes of illustration, if the sign or other apparatus is to be energized for approximately two cycles and then deenergized for two cycles alternately, switches 25 and 33 are closed and the potentiometers or variable resistances 21 and 29 set at minimum. If for a widely different time of one minute on and one minute off, the same switches are all opened and the variable resistances 22 and 31 set at maximum. However, if instead it is desired that the controlled device shall be energized for a period of thirty seconds and deenergized for a period of fifteen seconds, switches 25 and 33 are opened and variable resistance 22 is set to give fifteen seconds of time, as shown on its dial, and variable resistance 31 is set to give thirty seconds time, as shown on its calibrated dial.

From the foregoing it will be apparent that an interrupter of wide range and simple adjustability and operation has been provided, and that the values given are purely representative of what can be effected, without changing the general assembly of the several elements such as the condenser, resistances, switches, etc., while at the same time it is recognized that at this time the principles of operation may not be fully understood. However, it has been proved that with a given combination of switches opened or closed and variable resistances set in accordance with a set plan, on and off time can be established for any desired time duration that current is to be delivered to and withheld from the apparatus under control.

In the operation of this interrupter, the plug 1 is connected to any suitable source of alternating current and the switch 2 is closed, thereby energizing the transformer 3' and causing current to energize the filaments of the tubes 7 and 8, heating the cathodes to the proper temperature for tube operation. At the same time bias voltage is applied to control grid 28 of the tube 8 from said transformer through potentiometer 11, relay contact 29 and grid resistor 35. This voltage is out of phase by 180° with the plate voltage of tube 8, said plate voltage being applied to the plate of tube 8 through relay coil 15 and switch 14, when this switch is closed. Since the grid of the tube 8 is negative with respect to the adjacent cathode of said tube, when the plate voltage is positive with respect to said cathode, the tube cannot pass current through the relay coil, and the relay remains deenergized. Current however can flow through relay contact 16, tube 7, variable resistances 21 and 22, switch 25 and condenser 23, permitting a positive charge to build up in said condenser, the duration of such charge depending upon the setting of the variable resistances 21 and 22 and switch 25. This positive voltage from the condenser is applied to the grid of tube 8 through resistance 27, and when the magnitude of the positive voltage is sufficient to cancel out or offset the negative voltage being applied to the grid of said tube, the tube passes current from its cathode 40 to its plate, said current flowing through the relay coil and energizing the relay, which operates to change the setting of the respective contacts. During the period just described, the controlled apparatus connected to the terminals 42 and 44 has been off, as it has received no current due to relay contact 17 hav-

ing been open. When said relay is closed, contact 17 closes and passes current to the controlled apparatus, thereby causing it to function. At the same time relay contacts 16 and 20 open and contacts 18 and 19 close.

The closing of contact 19 and opening of contact 20 connects resistances 35 and 37 in series across the voltage supply potentiometer 11, and decreases the negative voltage applied to the grid of tube 8 through resistance 35. The closing of contact 18 places variable resistances 29 and 31, fixed resistance 30 and switch 33 across or in shunt with condenser 23, permitting the positive voltage in said condenser to discharge the length of time required, depending upon the setting of the variable resistances 29 and 31 and switch 33. This is possible since closing of the relay has also opened contact 16, stopping the flow of current through tube 7, said current having been previously employed to charge said condenser. As the positive voltage in said condenser leaks off through the variable resistances 29 and 31 and fixed resistance 30 and switch 33, the potential of the voltage drops, and the positive voltage delivered to the grid of said tube likewise drops, and the positive voltage will in a given time reach a point where it becomes less than the negative voltage passing through the resistance 35, and when this condition is reached the tube's grid again becomes negative and the tube stops firing or passing current through the relay, so that the latter then opens. This restores the contacts to their original positions and the cycle of operation is repeated.

Potentiometer 11 is employed to adjust the bias voltage delivered to tube 8, so that when switch 25 is opened and variable resistances 21 and 22 are set at maximum, a period of approximately one minute will elapse before the positive voltage in condenser 23 attains such magnitude as to cause current to flow in said tube and close said relay. Potentiometer 37 is employed to adjust the bias voltage delivered to said tube, so that when the switch 33 is open and variable resistances 29 and 31 are set at maximum, a period of about one minute will elapse before the positive voltage in the condenser reaches the minimum necessary to allow the negative voltage on the tube to stop the tube from passing current.

In the foregoing description there has been described an embodiment of the invention which gives a very wide range of period variations, but for those cases or installations in which a substantially narrower range will suffice, a modification embodying the same principle of operation comprises the elimination of resistance 11 and adjustable contact 12, and the direct connection of wire 32 to the free end of winding 10; omission of the secondary winding 4, if desired, and substitution of batteries or other source of current for heating the tube filaments 5 and 6, which substitution as a matter of fact can be employed in either form of the device; and omission of variable resistance 21, switch 25, variable resistance 29, fixed resistance 30 and switch 33. Also relay contact 19 may be omitted and the two wires leading thereto on the drawing permanently connected together. On the other hand, by adding an additional contact to said relay between wire 13 and a third terminal (not shown), an additional output will be provided which will permit a second light, or other type of electrical device, to be energized alternately with whatever device may be connected to terminals 42 and

44. Furthermore, an additional contact can be added connected with two additional terminals, so that another apparatus having its own independent power supply can be turned on and off by the operation of the device herein described. This modification is shown in Fig. 2.

Having thus described my invention, what I claim and desire to protect by Letters Patent of the United States is:

An electronic interrupter, comprising a rectifier tube and a thyratron tube, an auto-transformer having a two-section primary and a secondary, the filaments of said tubes being heated from said secondary, one section of said primary being connected to a source of alternating current and the other section being connected to one side of said current source through an adjustable resistance, a relay connected to said source and having a normally closed contact controlling the passage of current from said source to the plate 20 of said rectifier tube, a second contact normally open and controlling the passage of current from said source to a discharge terminal, the cathode of said rectifier tube being connected through a pair of variable resistances in series, the second resistance being provided with a switch-controlled shunt, and a condenser connected with the first-mentioned current source, the rectifier side of said condenser being connected through a normally open relay contact, a variable resistance, a fixed resistance and a switch-shunted

5 switch to the opposite side of said condenser, the rectifier side of said condenser being also connected through a fixed resistance to the control grid of said thyratron tube and through a fixed 10 resistance and a variable resistance to an adjustable contact on said auto-transformer resistance, said last-mentioned adjustable resistance being shunted by a normally closed relay contact, the connection between said last-mentioned pair of fixed and variable resistances being connected through a normally open relay contact and another fixed resistance with the second-mentioned section of said transformer and current source, and the suppressor grid and cathode of said thyratron tube being connected to a second discharge terminal and one side of said current source.

WALTER P. MENKHAUS.
